UNITED STATES PATENT OFFICE.

ROLAND B. BOURNE, OF HARTFORD, CONNECTICUT, ASSIGNOR, BY MESNE ASSIGNMENTS, TO THE MAXIM SILENCER COMPANY, OF HARTFORD, CONNECTICUT, A CORPORATION OF CONNECTICUT.

SILENCER.

Application filed May 16, 1928. Serial No. 278,224.

This invention relates to devices for silencing the exhaust of internal combustion engines, the intake of air compressors, or the like. The term "silencing" is used in a broad significance, having relation to the reduction to an unoffensive amplitude of sound waves whether of audible or of subaudible frequencies. The object of the invention is to provide a simple and compact device presenting a minimum of resistance to gas flow which will be effective in silencing the noise source to which it is attached.

Sound waves of the lower frequencies, either audible or subaudible, predominate in certain types of noise creating apparatus to such an extent that if they are removed the frequencies remaining are unobjectionable. The apparatus herein described is of the filter type, blocking the passage of certain low frequency sound waves while permitting the transmission of those of certain higher frequencies. Low frequency sound waves may present their disagreeable effects directly to the ear, in case they are above the limit of audibility; or, while themselves inaudible, may create disturbances by shaking buildings, rattling windows, or the like.

For attenuating such low frequency sound waves, I make use of the principles of the acoustic wave filter, a device capable of attenuating sound waves of certain frequencies and depending, for its action, not upon friction (or baffling) but upon acoustic reaction between suitably disposed series and shunt elements comprising the acoustic network. In general, the series elements are formed by the main acoustic channel through the device, while the shunt elements comprise chambers or other cavities suitably coupled to the main acoustic channel. Various arrangements are possible, giving correspondingly different attenuation versus frequency characteristics. The simplest of acoustic wave filters consists of a main acoustic channel having laterally disposed side branches suitably coupled, as by holes, to the main or series passageway, at intervals along the length thereof. The side branches may be tubes or chambers, or combinations thereof.

Every acoustic wave filter has more than one pass band of frequencies and more than one attenuation band. It is obvious, where the filter is primarily intended as a silencer,

that the attenuation bands should be as broad as possible. Recourse is made, therefore, in the present invention, to a disposition wherein the attenuation versus frequency characteristics of more than one acoustic system are superimposed in such a way that there results a wide band of sound frequencies which suffer attenuation.

Referring to the drawings:

Fig. 1 is a diagrammatic view illustrating the principle of my invention;

Fig. 2 is a longitudinal section through one form of apparatus embodying my invention;

Fig. 3 is a section through the apparatus on line 3—3 of Fig. 2; and

Figs. 4 and 5 are detail sections of modifications.

Referring first to the diagrammatic representation of Fig. 1, the sound waves enter the acoustic channel 10 and divide into the four side branches 11, 12, 13 and 14. These side branches have gaps 15 by which acoustic coupling is established with the side chambers 16, 17, 18 and 19. The continuations of the side branches, denoted in the drawings as 20, 21, 22 and 23, enter the common outlet acoustic channel 24 at intervals along the length thereof. It is to be noted that, in all the dispositions shown in the drawings, the first cross branch encountered upon entering the device communicates with the outlet channel at a point farthest removed from the final outlet, whereas the last cross branch leaving the inlet passageway communicates with the outlet channel at a point nearest the final outlet; the intermediate cross branches being correspondingly disposed.

The arrangement shown in Fig. 1, while primarily intended as a schematic representation of my invention, may form a practical embodiment, the side branches 11, 12, etc. being formed as pipes and the side chambers 16, 17, 18, 19, as cylinders surrounding the pipes and communicating therewith by means of coupling holes, slots or the like. Such an embodiment of the invention is, however, unwieldy, and the more compact arrangement of Fig. 2 is preferred.

In Figs. 2 and 3, I have shown a simple structure having the fundamental characteristics of the idealized arrangement of Fig. 1. The various parts are preferably made

of sheet metal secured together by welding at their lines of contact, and hence no rivets or bolts have been shown in the drawing. The structure is confined within a cylindrical casing 30 having headers 31 and 32 at its ends. Pipes 33 and 34 leading out of these headers may be of such length as desired for attachment to the structure to be silenced, the apparatus functioning when connected in either direction.

Within the cylinder 30 is a second shell 35 secured at one end to the header 32 and spaced from the casing 30 so as to form an annular acoustic channel 36. The other end 15 of the inner shell is closed by a header 37 spaced from the header 31 to form a chamber 38 connecting with passageway 36. Between the header 37 and the header 32 are three partitions 39, 40 and 41, serving to 20 divide the inner casing into four spaced compartments 42, 43, 44 and 45. The number of these compartments may be changed as desired, although in general the mathematical ideal will be approached more closely the 25 higher the number. For practical purposes, however, four will usually be found sufficient.

Within the compartments are side branches 46, 47, 48 and 49, each conveniently formed by a piece of sheet metal bent in circular 30 form 50 at its center, and having its sides 51 converging as is clearly shown in Fig. 3. The partitions 39, 40 and 41 and the header 32 are provided with central holes in alignment with the circular portions 50 of the 35 side branches, so that the composite structure constitutes a central circular acoustic channel 52 closed at one end by header 37 and opening out through pipe 34 at the other, and having side branches 46, 47, 48 and 49.

40 These side branches are preferably angularly arranged with respect to each other, each of them being advanced at a right angle from the preceding one. The walls 51 terminate short of the inner wall of the casing 35, leaving coupling openings 53 corresponding to the coupling openings 15 in Fig. 1, where the side branches are coupled to the otherwise closed acoustic side chambers. Opposite the end of each side branch 45 the casing 35 is slotted at 54 to provide a short passage connecting the annular acoustic channel 36 with the side branches, and, through the openings 53, with the closed side chambers 42, 43, 44 and 45.

55 It will be apparent that the structure of Figs. 2 and 3 corresponds to the idealized case of Fig. 1 if the coupling openings 15 in the latter be shifted to one end of the side branches instead of being located centrally. If it is desired to vary the position of the 60 coupling opening to correspond with the central location of Fig. 1, the modified construction of Fig. 4 or 5 may be used. In Fig. 4, the walls 51 are replaced by pieces 60

surrounding the central acoustic channel 52 and extending parallel to each other part way to the inner casing 35. The walls of this casing are spaced at 61 and are bent inwardly as at 62 toward the pieces 60, leaving 70 a coupling opening 63 serving the same purpose as the opening 53. In Fig. 5 a similar construction is shown, except that the walls 65 which surround the central acoustic channel are extended all the way to the casing 35 75 and are preferably welded in place, communication to the side chambers being had through coupling holes 66 in the walls.

What I claim is:

1. A silencer comprising an annular acoustic channel, a central acoustic channel, a plurality of connecting side branches, and side chambers communicating individually with the side branches but otherwise closed. 80

2. A silencer comprising a pair of main 85 acoustic channels, a plurality of side branches joining the main acoustic channels, and side chambers communicating individually with the side branches but otherwise closed.

3. A silencer comprising an annular acoustic channel, a central acoustic channel, a plurality of side branches longitudinally and angularly spaced from each other, and side chambers communicating individually with the side branches but otherwise closed. 90

4. A silencer comprising a pair of casings, one within the other, presenting an annular acoustic channel between them, a plurality of partitions within the inner casing dividing it into separate compartments, 100 a central acoustic channel through all of said compartments, walls within each of said compartments dividing it into a side branch and a side chamber, and coupling openings from each compartment to the 105 annular acoustic channel and from each side branch to its contiguous side chamber.

5. A silencer comprising a pair of casings, one within the other, to present an annular acoustic channel between them, a plurality 110 of partitions within the inner casing dividing it into separate compartments, a sheet of converging U-form extending between each of said partitions and terminating short of the inner casing, slots in the inner casing 115 opposite the converging portions of said sheets, and central openings through the partitions forming with the sheets a central acoustic channel.

6. A silencer comprising a pair of acoustic channels, a plurality of side branches extending therebetween and connecting to said acoustic channels at intervals along the lengths thereof, and side chambers communicating individually with said side branches. 120

7. A silencer comprising a pair of acoustic channels, a plurality of side branches extending therebetween and connecting to said acoustic channels at intervals along the lengths thereof, and side chambers commun- 125

icating individually with said side branches but otherwise closed.

8. A silencer comprising an inlet acoustic channel, an outlet acoustic channel, a plurality of side branches extending therebetween and connecting with said inlet and outlet channels at intervals along the lengths thereof, the side branch communicating with the inlet channel at the point nearest the inlet to the silencer opening into the outlet channel at a point farthest removed from the outlet of the silencer, and side chambers communicating individually with said side branches.

15 9. A silencer comprising an inlet acoustic channel, an outlet acoustic channel, a plurality of side branches extending therebetween and connecting with said inlet and

outlet channels at intervals along the lengths thereof, so disposed that, starting from the 20 inlet of the silencer, the side branches 1, 2,— n , open into the outlet channel in the order n ,—2, 1, viewed from the outlet end of the outlet channel, and side chambers communicating individually with said side 25 branches.

10. A silencer comprising a pair of main acoustic channels, a plurality of side branches joining the main passages, said side branches varying in cross-sectional area along their 30 lengths, and side chambers coupled acoustically to the side branches but otherwise closed.

In testimony whereof I have affixed my signature.

ROLAND B. BOURNE.
